DESIGN FOR A HAND BAG

David Karron, Brooklyn, N. Y.

Application July 21, 1933. Serial No. 48,781

Term of patent 3½ years

To all whom it may concern:

Be it known that I, DAVID KARRON, a citizen of the United States, residing at Brooklyn, in the county of Kings and the State of New York, have invented a new, original, and ornamental Design for Handbags, of which the following is a specification, reference being had to the accompanying drawing, forming part thereof.

Fig. 1 is a side elevation of a handbag, showing my new design.

Fig. 2 is an end elevation, and

Fig. 3 is a top plan view thereof.

The shaft of the key is fixed in the spaced members, yieldingly mounted on one of the frame parts to rock transversely, said members having recesses in their lower sides to receive projections on the other frame part.

I claim:

The ornamental design for a handbag as shown and described.

DAVID KARRON.
